UNITED STATES PATENT OFFICE.

LOUIS B. PRAHAR AND CHARLES S. SHEPARD, OF BROOKLYN, NEW YORK.

COMBINED BUTTON-HOOK AND CORKSCREW.

SPECIFICATION forming part of Letters Patent No. 349,741, dated September 28, 1886.

Application filed January 25, 1886. Serial No. 189,731. (No model.)

To all whom it may concern:

Be it known that we, LOUIS B. PRAHAR and CHARLES S. SHEPARD, of the city of Brooklyn, county of Kings, and State of New York, have 5 invented a new and useful Improvement in Combined Button Hooks and Corkscrews, of which the following is a full, clear, and exact description.

Reference is to be had to the accompanying 10 drawings, forming a part of this specification, in which similar letters of reference indicate corresponding parts in all the figures.

Figure 1 is a side elevation of a combined 15 button-hook and corkscrew. Fig. 2 is a front elevation of the same. Fig. 3 is a side elevation of a part of a combined button-hook and corkscrew, showing a modification. Fig. 4 is a side elevation of a part of a combined button-hook and corkscrew, showing another 20 modification.

The object of this invention is to provide a 25 combined button-hook and corkscrew constructed in such a manner that it can be readily carried in the pocket, and can be conveniently used in either capacity.

The invention consists in the combination, 30 with the button-hook, of a hinged corkscrew, as will be hereinafter fully described.

A is a button-hook in the middle part of the 35 handle of which is formed a bend, B. In a slot in the bend B is pivoted the shank of a corkscrew, C, so that the said corkscrew can be turned down parallel with the handle of the button-hook or can be turned up at right angles with the said handle. The corkscrew 40 C is kept in place when turned down by catching its point in a recess, D, formed in the button-hook handle near its outer end, a bend, E, being made in the said part of the handle to

bring the recess D into proper position for the 40 point of the corkscrew to engage with it.

If desired, the slotted middle part of the button-hook handle can be made straight, as shown in Figs. 3 and 4, in which case a bend, F, must be formed in the shank of the cork- 45 screw C, to adapt the said corkscrew to be turned down parallel with the said handle; or a short stud, G, can be riveted or otherwise secured to the handle of the button-hook A, the said stud being made of such a height that 50 the corkscrew C can be turned down parallel with the button-hook handle.

The construction first described is preferred as being neater and more pleasing to the eye. 55 With this construction the implement can be used as a button-hook with as much facility as though it had no corkscrew attachment, can be used as a corkscrew as conveniently as though the button-hook were an ordinary corkscrew-handle, and can be carried in the pocket with 60 as much convenience as an ordinary button-hook.

Having thus described my invention, what I claim as new, and desire to secure by Letters Patent, is—

The herein-described combination implement, consisting of a button-hook, A, and a corkscrew, C, hinged to the said button-hook, substantially as herein shown and described, whereby the implement can be conveniently 70 carried in the pocket and readily used in either capacity, as set forth.

LOUIS B. PRAHAR.
CHARLES S. SHEPARD.
